UNITED STATES PATENT OFFICE.

MARY W. CONWAY, OF CINCINNATI, OHIO.

CASING AND GUIDE FOR WINDOW-SHADES, &c.

965,441.

Specification of Letters Patent. Patented July 26, 1910.

Application filed November 17, 1909. Serial No. 528,576.

To all whom it may concern:

Be it known that I, MARY W. CONWAY, a citizen of the United States, residing at Cincinnati, in the county of Hamilton and 5 State of Ohio, have invented new and useful Improvements in Casings and Guides for Window-Shades, &c., of which the following is a specification.

My invention relates to devices for the 10 protection and use of window shades, its object being to provide an article of convenient use in connection with the ordinary window-shades and the like, (such as maps, etc.) carried upon spring rollers, whereby 15 they may be preserved and protected while in use and out of use from dust or other injury.

To this end my invention consists in a cylindrical casing, adapted to contain the 20 spring roller commonly used with window curtains, and to engage the roller upon its projecting spindles, and thus completely incase the curtain.

The casing is provided with a longitudinal 25 opening with a marginal curb wall extending outwardly, forming a guide to the curtain in winding on or off the roll. The inner surfaces of the curb wall may be provided with a covering of plush or other suitable 30 material, to act as a brush and remove dust from the curtain on entering the casing; and the brace or rib attached to the lower edge of the curtain to carry the operating ring, forms a complete closure of the mouth of the 35 curbed opening, when the curtain is out of use, to prevent the entrance of dust, etc. The casing thus completely covers and protects the curtain, its roller and winding mechanism, and also preserves a constant operative 40 relation between the curtain and the winding spring of its roller; so that the usual annoyances of disarrangement are avoided.

When entirely detached and stored away, 45 the casing affords complete protection from light, insects, dust, etc.

My invention is illustrated in the accompanying drawings, in which:

Figure 1 is a front elevation of my device 50 complete and in position. Fig. 2, a perspective view of one end portion of the casing sectioned across to show the relation of the curtain roller thereto, and the relation of curtain to the guide opening and guide curb. 55 Fig. 3, is a detail view of the same extreme end of the casing, showing the projection of

the squared spindle of the curtain roller; and Figs. 4 and 5 are details of the opposite end-portion of the casing and of the end cover respectively, showing the extension 60 feature.

Referring now to the drawings, A designates a cylindrical casing, preferably of sheet metal, of sufficient length to take in a curtain roller *r* of the ordinary type, having 65 spring winding mechanism. The spindles, *s*¹, *s*², of the roller project through the ends of the casing—the squared spindle *s*² of the roller spring mechanism projecting through a corresponding squared hole *s*³ in the casing, which prevents rotation and with which it thus coöperates in the same manner as with its normal supporting bracket *b*², and also with the bracket *b*² in retaining the casing A in normal relations with the curtain 70 and the window frame. The casing A has a longitudinal opening at one side which is extended outward by a marginal curb *d*, forming parallel walls. Through the space thus inclosed, the curtain passes and is 75 guided to proper seating on its roller *r*. A rib *c*¹ is attached to and across the free end of the curtain and is formed to seat upon or within the mouth of the exit opening of the curb *d*.

The curb wall *d* is preferably lined throughout by plush or similar material to sweep both sides of the curtain free of dust in entering.

The casing and guide may be made of 80 lengths to fit the width of curtains according to the standard sizes commonly in use; but an extensible casing may be made by using a main cylinder A of minimum length, but with longitudinally extending curb walls 85 *d*¹, *d*², which are to be shortened as far as may be necessary and the end of one bent over as shown in Fig. 4. The end cap, A¹ has a slot *a*, at one side formed to inclose the extension curb outwardly and to slip over 100 the cylinder A to place—as indicated in Fig. 1.

There is thus formed a complete casing which is practically an adjunct to the spring curtain-roller in common use, requiring no 105 change whatever in the roller, or its brackets (and their mode and place of attachment), or in the curtain or its attachment to the roller; and which, when the curtain is wound on its roller to the highest limit, forms a 110 dust-proof protection and storage casing. It also, while in use, prevents the settling of

dust upon the curtain at the top of the roller (a very common source of injury); and, besides, brushes off the dust at both sides of the curtain before it passes into the casing 5 and upon the roller.

The device, as will be obvious, can be used for maps, pictures, etc.

I claim as my invention and desire to secure by Letters Patent of the United States:

- 10 1. A casing for curtains consisting of a cylindrical covering pierced at its ends for the spindles of the curtain roller, and adapted to engage one of said spindles non-rotatively, having a longitudinal exit-opening provided with a curb-wall constituting a winding guide for the curtain; said curb-wall being formed of substantially parallel oppositely projecting spaced members having a lining of cloth or similar material to brush dust from the sides of the curtain in 15 entering.
- 20

2. A casing for spring roller window shades consisting of a cylindrical covering closed at one end and pierced through its end wall for the projection of one roller 25 spindle, and having a longitudinal opening at one side provided with a curb wall extending the opening outward, and extensions of said wall beyond the open end of the casing, in combination with a shorter 30 section of cylindrical casing closed at the outer end and pierced for the projection of the other spindle of the roller, slotted at one side and adapted to slip over and upon the main casing as an extension thereof. 35

In testimony whereof I have hereunto set my hand in presence of two subscribing witnesses.

MARY W. CONWAY.
